UNITED STATES PATENT OFFICE.

HENRY RAMSAY, OF LONDON, ENGLAND.

CUSHION-PAD FOR HAT-PINS.

1,161,527.

Specification of Letters Patent. Patented Nov. 23, 1915.

Application filed June 19, 1914. Serial No. 846,043.

To all whom it may concern:

Be it known that I, HENRY RAMSAY, a subject of the King of Great Britain and Ireland, and resident of South Bermondsey, 5 London, S. E., England, have invented certain new and useful Improvements in Cushion-Pads for Hat-Pins, of which the following is a specification.

This invention relates to an improved pad 10 for use on hats and head-dresses to receive the point of the hat-pin.

It relates particularly to devices for the foregoing purposes in which a pad of cork or the like is attached to the interior of the 15 hat and adapted to receive the point of the pin.

The present invention consists of a particular type of pad formed in composite fashion of layers of cork inclosing a layer 20 or core of felt secured together in the manner herein described, whereby the pin-point cannot be thrust right through under normal pressure, and a degree of grip is present to prevent accidental withdrawal of the pin.

25 The invention is illustrated by the accompanying sheet of drawings, in which:—

Figure 1 is a diagram to show the general arrangement of the pad and pin *in situ*. Fig. 2 is a section of the pad. Fig. 3 is a 30 front view thereof; and, Fig. 4 is a view of detached members hereinafter referred to.

The pad consists of layers of cork *a* inclosing a core of felt *b*; a backing of buckram or stiff linen *c* is secured by a thick 35 coating of shellac, glue or other hard-drying adhesive, preventing penetration of the pin-point when it has pierced completely through the various layers. A piece of linen or the like *d* covers the whole and is attached to backing *c* at its edges. In order to 40 form an efficient and springy gripping pad,

the layers are preferably secured together by a rim of hard-drying adhesive as above specified around their edges as seen at *e* in Fig. 4. The pad is sewn, struck or otherwise fixed in the hat as seen in Fig. 1. As seen in Figs. 2 and 3, a margin or lap *f* of buckram or the like is formed for attaching or other purposes.

Having now described my invention, what 50 I claim as new and desire to secure by Letters Patent of the United States is:—

1. A cushion pad and point-protecting shield for hats comprising outer and inner cork layers and an interposed felt layer, said 55 layers being arranged in compact relation and secured together at their outer edges by a thin ring-like coating of a hard drying adhesive, and a fabric covering member for inclosing said layers and providing attach- 60 ing means.

2. A cushion pad and point protecting shield for hats comprising outer and inner cork layers and an interposed felt layer, said 65 layers being arranged in compact relation and secured together at their outer edges by a thin ring-like coating of a hard drying adhesive, a fabric covering member inclosing said cushion, and a stiff fabric backing member, said backing member being secured to 70 the inner cork layer by a thick coating of a hard drying adhesive, said cover and backing extending beyond the outer edges of the laminated cushion to provide an annular attaching ring.

In testimony whereof I have affixed my 75 signature in presence of two witnesses.

HENRY RAMSAY.

Witnesses:
